SAFETY TOOL CHECK.

Application filed July 6, 1926. Serial No. 120,686.

In withdrawing tools from a well, particularly cable tools, the control head or the like at the top of the casing, is frequently hit; causing the tool to break off of the cable and fall back into the well; causing serious damage.

An object of my invention is to provide a novel check for the well tools to prevent their accidentally falling into the well.

10 Another object is to provide a simple and effective tool check which will automatically act to catch the tool if said tool is accidentally dropped into the well.

Other objects, advantages and features 15 of invention may appear from the accompanying drawing, the subjoined detailed description, and the appended claims.

In the drawing,
20 Fig. 1 is a longitudinal sectional view of my check in position in a casing.

Fig. 2 is a sectional view taken on line 2-2 Fig. 1.

Fig. 3, is a sectional view taken on line 3-3 Fig. 1.

25 Referring more particularly to the drawing; a pipe section 1, approximately the same diameter as the casing 2, is secured to the casing and is positioned below a control head or the like 3 mounted on pipe sections 30 4 secured to the upper end of said pipe.

In the pipe section 1 is pivotally mounted a plate 5, which normally rests across said pipe to close the same. A ledge 6 is provided in the pipe upon which the plate 5 rests. A rod 7 extends through, and is secured in the plate 5 and said rod is journaled 35 in the walls of the pipe 1. One end of the rod is bent downwardly and a weight 8 is se-

cured thereto, whereby the plate 5 is always carried to a closed position resting across the 40 pipe 1.

A slot 9 is formed in the plate 5 through which the cable, drill stem or the like extends. The slot is not wide enough to permit passage of the bit 10, but the bit strikes 45 the plate; swinging it upwardly to permit its passage, after which the weight 8 closes the plate and if the bit should fall it would strike and rest on said plate.

A recess 11 is provided in the pipe section 50 1 to accommodate the plate 5 when it is swung upwardly; thus leaving a free passage for the tools or the like.

When it is desired to lower tools into the well, the weight 8 may be grasped and the 55 plate 5 swung to open position, leaving the passage clear.

Having described my invention I claim—

1. A tool check adapted to be positioned 60 in a well casing, comprising a plate normally resting across the casing, said plate having a slot therein to permit passage of the drilling stem or the like, a rod upon which said plate is mounted and a weight depending from said rod whereby the plate is urged 65 to a position across the casing.

2. A tool check comprising a pipe section 70 adapted to be positioned in the casing, a plate having a slot therein through which the drill stem or the like extends, a ledge adapted to support said plate when in closed 75 position, a rod secured in the plate, and a weight depending from said rod whereby the plate is normally urged to closed position.

In testimony whereof I affix my signature.

GUSTAVE J. CORMIER.
